UNITED STATES PATENT OFFICE.

JOSEPH F. WIESNER, OF ELLIS, KANSAS.

MEASURING AND CUTTING MACHINE.

Application filed August 13, 1921. Serial No. 492,169.

To all whom it may concern:

Be it known that I, JOSEPH F. WIESNER, a citizen of the United States, residing at Ellis, in the county of Ellis and State of

5 Kansas, have invented new and useful Improvements in Measuring and Cutting Machines, of which the following is a specification.

This invention relates to an apparatus 10 for measuring, rolling and cutting oil cloth and the like, the general object of the invention being to provide means for supporting a plurality of rolls of cloth, with means whereby the cloth on any desired roll 15 can be attached to a winding roll to wind off the quantity of cloth desired by the customer, with means for measuring the cloth being wound upon the winding roll and cutting means for severing the cloth.

20 Another object of the invention is to provide a simple form of measuring device for measuring the cloth and means for easily and quickly attaching the cloth to the winding roll.

25 A further object of the invention is to provide a simple construction of cutting means and also to form the cutting means so that the blade thereof is enclosed so that there is but little danger of the operator 30 injuring himself.

This invention also consists in certain other features of construction and in the combination and arrangement of the several parts, to be hereinafter fully described, 35 illustrated in the accompanying drawings and specifically pointed out in the appended claims.

In describing my invention in detail reference will be had to the accompanying 40 drawings wherein like characters denote like or corresponding parts throughout the several views, and in which:—

Figure 1 is a plan view of the invention.

Figure 2 is a front view thereof.

45 Figure 3 is a side view.

Figure 4 is a section on line 4—4 of Figure 1.

Figures 5, 6, 7 and 8 are detail views.

In these views 1 indicates a base frame 50 upon which the various parts of the apparatus are supported. An inverted V-shaped frame 2 is connected with each side of the base frame, at the rear thereof, these V-shaped frames being provided with the 55 downwardly inclined notches 3 for receiving the ends of the rolls 4 upon which the

cloth is wound. Thus a plurality of rolls of cloth can be supported by the apparatus so that the customer can choose from a variety of patterns.

60 The top bars of the base frame are provided with notches 5 which are situated in front of the supporting frames 2 and are intended to receive the roll of cloth which has been picked out by the customer. This cloth is 65 passed between the small roller 6, which is supported on the uprights 7, forming part of the base frame and which are located at the center of the same, and the roller 8, which is carried at the front end of the 70 curved frame 9 which has its other end pivotally supported at the bottom of the base frame as at 10 Figures 1 and 4. This frame 9 consists of a pair of curved bars held in spaced relation by the pivot 10, the roller 75 8 and the cross piece 11. This frame can be swung upwardly to separate the rollers 6 and 8 to permit the cloth to be passed between the rollers. The frame 9 carries a dial 12 and a finger 13 cooperates with this 80 dial and the shaft of this finger is connected with a gear 14 which meshes with a gear 15, secured to a roller 8. Thus the cloth being pulled between the rollers will cause the same to rotate and the movement of roller 8 will 85 be communicated to the finger 13 so that the cloth will be measured as it is being unwound from the roll in notches 5.

I provide a winding roll 19 upon which the cloth is wound after it passes between 90 the measuring rolls 6 and 8. This winding roll is supported at the outer end of the base of the frame and it has a spherical member 20 on one end which is fitted to and held in place by a $\frac{3}{4}$ spherical receptacle, composed 95 of a semi-spherical socket 21 and two segments 22 which are fastened to the socket Figure 5. The receptacle encloses the spherical member 20 and acts as a journaled bearing for allowing the winding roll to revolve 100 while rolling up the cloth. The receptacle is movably held to the frame by means of the bolts 23 and the springs 24 on said bolts. The other end of the winding roll is provided with a square socket 25 Figure 7 which 105 is adapted to receive a square part 26 formed on the inner end of a stub shaft 27 which is journaled in the base frame and which is adapted to be rotated by a crank handle 28 Figure 1. It will thus be seen that the roll 110 19 can be moved longitudinally by pressing it towards the spherical receptacle, thus

moving said receptacle on the bolts and against the action of the springs. This will free the other end of the roll from the stub shaft and then the roll can be swung to an inclined position so that the operator can insert his finger or thumb into the end of the roll of cloth, which projects beyond the end of the roll, due to the removal of the stub shaft, and so grip the cloth and pull the same off the roll. It is not necessary to handle the roll itself other than swing it into an inclined position.

I also provide simple means for connecting the end of the cloth with said winding roll, such means consisting of an angular clamp 29 Figures 5 and 6 which engages a part of one end and a part of the circumference of the roll so as to clamp the cloth to the roll. This clamp is yieldingly held in clamping position by the spring 30 and is moved into unclamping position by the plunger 31 engaging a rod 32 which is located in a hole in the roll and engages the clamp. The plunger is provided with a notch 33 having an inclined part 33' which will engage the inner end of the rod 32 and force said rod outwardly when the plunger is pulled out and thus move the clamp to unclamping position. When the plunger is pushed inwardly the spring 30 will return the parts to clamping position. The roll is provided with a recess 34 for receiving the head of the plunger when the same is pushed inwardly to permit the spring to move the clamp to clamping position. The plunger can be pushed inwardly while it is covered by the cloth as it is simply necessary to place pressure on that part of the cloth which is over the head of the plunger.

The severing means comprises a stationary bar 35 extending across the upper part of the base frame adjacent its front end and having its upper edge rounded and provided with the centrally located slot 36 Figure 8 for receiving the cutting edge of the knife 37. This knife 37 is carried by a knife bar 38 which has its lower edge provided with a semi-circular cavity 39 in which the cutting part of the knife is located. This cavity will receive the rounded upper edge of the bar 35 when the knife is in lowered position. The extended parts of the knife bar 38 which form the cavity act as dogs to prevent the operator from injuring himself by the knife. This bar 38 is connected with the upper ends of the vertically arranged rods 40 Figure 3 which are slidably mounted in the base frame and have their lower ends connected together by the foot board 41. Springs 42 on the lower parts of the rods 40 tend to hold the rods in raised position with the knife bar well above the measuring and winding rolls so that the operator can readily pass his arms and hands under the knife bar in placing the cloth between the meas-

uring rolls and connecting it with the winding roll.

When a sufficient amount of cloth has been wound from the roll in notches 5 upon the winding roll the operator depresses the board 41 by his foot so as to bring the knife down upon the bar 35 and thus sever the cloth.

From the above it will be apparent that the cloth after having its roll positioned in notches 5 can be passed between the rollers 6 and 8 by swinging the frame 9 upwardly to raise the roll 8 to permit the cloth to be passed between the rolls. The frame 9 is then lowered to place roll 8 in contact with the cloth. The end of the cloth is then connected with winding roll 19 by means of the clamp 29 and then this winding roll is turned by its crank to wind the cloth thereon. When a sufficient amount of cloth has been withdrawn from the roll and wound upon the winding roll, this amount being indicated by the finger 13 on dial 12, the knife is lowered to sever the cloth.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:—

1. An apparatus of the class described comprising a supporting frame, having bearings therein for supporting a roll of cloth, a frame pivotally mounted to the supporting frame, a roll in the pivotally mounted frame, a roll in the main frame upon which the first mentioned roll is adapted to rest when the pivoted frame is in lowered position, measuring means actuated by the first mentioned roll, a winding roll and severing means located between the winding roll and the rolls of the measuring device.

2. An apparatus of the class described comprising a supporting frame, means for holding a roll of cloth thereon, a measuring device for measuring the cloth being unrolled from the roll, a winding roll, a spherical member at one end thereof and a socket at the other end, a socketed plate for receiving the spherical member, means for yieldingly holding the plate to the supporting frame, a stub shaft having a projection thereon engaging the socket in the winding roll, a crank handle connected with the stub shaft and severing means located between the winding roll and the measuring device.

3. An apparatus of the class described comprising a base frame, a pair of roll supporting frames having notches therein for receiving the ends of the rolls, bearings in the base frame for receiving the ends of

one of the rolls, a winding roll in the front of the base frame, means for detachably holding the roll in place, a crank handle for rotating the roll, a frame swingingly connected with the base frame, a pair of measuring rolls, one of which is carried by the

base frame, measuring means on the pivoted frame and actuated by the roll carried thereby and severing means arranged between the 10 measuring device and the winding roll.

In testimony whereof I affix my signature.

JOSEPH F. WIESNER.
